(57) **CLAIM**

The ornamental design for an infant bed accessory, as shown and described.

DESCRIPTION

FIG. 1 is a perspective view of an infant bed accessory showing a new design;

FIG. 2 is a front view thereof;

FIG. 3 is a back view thereof;

FIG. 4 is a right side view thereof, the left side being a mirror image thereof;

FIG. 5 is a top view thereof;

FIG. 6 is a bottom view thereof;

FIG. 7 is a right side cross-sectional view thereof;

FIG. 8 is a perspective view of the infant bed accessory in an installed configuration;

FIG. 9 is a right side view thereof;

FIG. 10 is a left side view thereof;

FIG. 11 is a back view thereof;

FIG. 12 is a front view thereof;

FIG. 13 is a top view thereof; and,

FIG. 14 is a bottom view thereof.

The dashed lines in the drawings illustrate both portions of the infant bed accessory and the environment of infant bed accessory, and form no part of the claimed design.
